DESIGN FOR A BRASSIÈRE

Samuel J. Reiner, New York, N. Y.

Application April 23, 1947, Serial No. 138,559

Term of patent 3½ years

(Cl. D20—4)

To all whom it may concern:

Be it known that I, Samuel J. Reiner, a citizen of the United States of America and a resident of the city of New York, in the county of Kings and State of New York, have invented a new, original, and ornamental Design for a Brassière, of which the following is a specification, reference being had to the accompanying drawing, forming a part thereof.

Fig. 1 is a perspective view of a brassière, showing my design, and

Fig. 2 is an enlarged view of a portion of the ornamental stitching of the breast portions of same.

The back of the brassière is conventional.

The characteristic feature of my design resides

in the combination on the brassière disclosed of the specific circular stitchings on the breast pockets, as shown.

I claim:

The ornamental design for a brassière, substantially as shown and described.

SAMUEL J. REINER.
